UNITED STATES PATENT OFFICE.

LESLIE W. CLAYBOURN, OF MILWAUKEE, WISCONSIN.

METHOD OF CONDITIONING PRINTING INK.

Application filed December 11, 1925. Serial No. 74,774.

Printing inks as usually manufactured are made of various kinds, grades and colors, and are then packed in barrels, drums, cans or other containers, and remain in such containers an indefinite length of time before they finally reach the consumer and are put into use in the printing press.

The ink so manufactured and delivered is in mixed state supposedly ready for use on the printing press, and when used, the printing ink is usually transferred from the container to the fountain of the printing press in the condition in which the printing ink is after the lapse of time during which it has remained in the container, on the assumption that the printing ink is in the same condition as when originally manufactured. I have found, however, that such printing ink has stiffened up and that a seeming separation of the ingredients has taken place, such lapse of time also causing "livering" of the printing ink, that is, causing the ink to become tough like leather, caused, I assume, by the mixing of certain driers with the printing ink when manufactured, especially driers containing sugar of lead, or other chemical driers.

It is the object of my invention to condition inks so manufactured and delivered, and to treat the same with my improved method just prior to use of the inks in the printing press.

In modern printing practice, clear definition of the printing lines is desirable, and rapid printing of the sheets or duplication of the printed matter on a web of paper is also desirable, in fact, the speeds with which printing is done under modern practice is extremely great, resulting in the rapid piling of printing sheets or thicknesses of web of printed paper upon one another, with a consequent smutting of the paper and off-setting of the printed surfaces of the sheet or portions of the web upon the rear surfaces of sheets or portions of the web superposed thereon, making expensive interleaving or other operations necessary.

It is the further object of my invention to remove these objections by so conditioning the ink that it will flow freely, to permit of its being applied to the surfaces of the printing lines by the form rollers to cover said printing surface without excess of ink; to permit its ready transference

from the printing surface to the paper, and to cause its rapid drying when transferred to the paper, in order to avoid smutting, off-setting and other objections incident to inks which may be sustained for a time in wet condition on the paper.

It is the further object of my invention to manufacture the printing ink which is to be packed in containers and to remain therein an indefinite length of time, as hereinbefore explained, with a substantially smaller proportion of drying ingredients than is now usual, or without such drying ingredients, and to supply a drying ingredient or drying ingredients, preferably in greater proportions than has heretofore been the practice in the manufacture of such ink, just prior to the use of said printing ink in the printing press, and to thoroughly mix, churn, whip and stir said drying ingredient or drying ingredients with such ink and to thoroughly aerate the mixture. The drying ingredient or drying ingredients thus employed are preferably quickly oxidizing drying ingredients.

My invention consists further in aerating the ink just prior to its use; and, further, in adding a so-called drier to the body of the ink and thoroughly mixing the same just prior to use of the ink in printing.

It may be here stated that while paper is referred to as the article being printed, my improved method relates to and covers printing on other surfaces as well.

My invention is further applicable in color printing, especially in color printing where the colors are superposed on the paper in successive steps while the paper is passing once through the printing press.

In carrying out my invention, I preferably transfer the ink from the container in which it has been stored to a bowl, and I thoroughly mix the ink by means of a suitable stirrer, and also preferably add a so-called drier to the ink, and thoroughly stir and aerate the same, which drier may, for instance, be a japan drier, or it may be a chemical drier, such as sugar of lead or other chemical driers. The amount of drier and the character of drier added to the ink will depend largely upon the kind, grade and color of the ink, the purposes for which it is to be used, and the kind of surface on which the printing is to be done, having

regard for the absorbing properties of the latter, and also of the temperature and humidity of the room where the printing takes place. The mixing is preferably done close to the printing press, so that the ink upon being mixed may be quickly transferred to the ink fountain of the printing press and promptly used in the printing.

I have illustrated an exemplification of relations of mechanism which may be employed in performing my improved method, although the same may be manually performed, or performed by other apparatus. An exemplifying apparatus is illustrated in the accompanying drawings, in which:

Fig. 1 is a side elevation of the inking end of a conventional printing press, having a mixing device in adjacency thereto, for mixing the ink in accordance with my improved method.

Fig. 2 is a plan view of the same.

Fig. 3 is a vertical axial section of the mixing device.

Fig. 4 is a plan view of the bowl and its support.

Fig. 5 is a cross-sectional detail of the releasable connection between the stirrer shaft and the stirrer, taken in the plane of the line 5—5 of Fig. 3.

30 The ink, as manufactured and delivered to the consumer, may be contained in a closed can 11, instanced as an example of an ink container.

35 The mixing device 12 is instanced as embodying a stirrer 13, shown as having releasable connection with a shaft 15, journaled in a bearing 16, of a rotatable plate 17, secured to a shaft 18, rotated in suitable manner. The shaft 18 is journaled in a bearing 19 of an arm 20, extending from a column 21 of the main frame. The arm has an internal gear 22 thereon, having an axis coincident with the axis of rotation of the shaft 18. A pinion 23 is on the shaft 40 15 and meshes with the internal gear. A shoulder 24 on the shaft 18, coacting with the bearing 19, maintains the plate in properly elevated position with relation to the arm, and a shoulder 25 on the shaft 15 co-45 acting with the pinion 23, and engagement of the lower end of the pinion 23 with the bearing 16, holds the shaft 15 in axial position with relation to the plate.

50 The releasable connection between the shaft 15 and the stirrer may be obtained by providing the lower end of the shaft with a hub 26, arranged to be received about the upper end of the shank of the stirrer, with a key connection 27 between said shaft and said hub and a thumb-screw 28 threaded in the hub, the inner end of the thumb-screw being received in a recess 29 in the upper end of the shank of the stirrer.

55 A mixing bowl 31 is arranged to be placed in a recess 32 of a support 33, shown as a

bracket above the base 34 of the column. Rotation of the bowl is prevented by providing the mixing bowl with ears 35 received in recesses 36 in the bracket.

Means are provided for causing ready approach and recession between the stirrer and the bowl, which may be accomplished by providing the arm 20 with bearings 41 about guide-rods 42 fixed to the frame. A screw-rod 44 is fixed to an upper arm 45 extending from the column, and has threaded engagement with a nut 46, journaled in a bearing 47 of the arm 20, the nut having a bevel pinion 48 thereon, engaged by a bevel pinion 49 on a shaft 50, journaled in bearings on the arm 20, and provided with a hand-wheel 51.

55 The shaft 18 is arranged to be driven in any suitable manner, which may be accomplished by providing the same with a bevel gear 53, having spline-key and groove connection with said shaft, and meshed by a bevel pinion 56 on a shaft 57 journaled in a bearing 58 on the upper arm. The shaft 57 is arranged to be driven by an electric motor 59, the rotor of which is connected with the shaft 57 by a usual flexible coupling 60. This motor may be a variable speed motor for imparting various speeds to the stirrer.

50 The shape of the stirrer is preferably such as to engage the side wall and bottom of the bowl so as to scrape the ink which impinges the wall of the bowl, away from such wall, so as to move it into the body of the ink in 100 the bowl, and to thoroughly whip and aerate the ink and produce a uniform consistency and color in the ink. The bottom of the bowl may have a central upwardly extending bulge 64 therein, forming an annular 105 depression 65 coincident with the annular path of the lower end of the stirrer about the bottom of the bowl. The stirrer may be of any suitable shape for producing a thorough stirring and mixing of the ink in 110 the bowl, and is preferably of such shape as to be readily cleaned.

55 The operation of the machine is such as to impart a rotary movement to the stirrer and also a planetary movement inside the wall 115 of the bowl. The path of rotary movement of the stirrer is preferably eccentric with relation of the annular cross-section of the bowl.

60 The ink from the container, in which it has been packed, is transferred to the mixing bowl, preferably while the bowl and stirrer are in separated relation. Approach between the stirrer and the bowl is preferably caused while the stirrer is rotating, 125 so as to include a continuously greater body of ink in the stirring operation. The desired amount of drier or oxidizing agent is added to the ink, preferably a little at a time during the stirring operation, until the 130

desired amount has been added. Approach between the stirrer and the bowl is continued until the stirrer coats with the bottom of the bowl, the stirring being then continued until the ink is conditioned.

In cases where an apparatus is used in which no approach between the stirrer and the bowl is provided for, the proper coactive relation between the stirrer and the bowl is obtained in suitable manner for providing a suitable stirring of the ink and the thorough mixing of the drying or oxidizing agent therewith.

I show an arrangement whereby the printing ink may be readily mixed and aerated. Bowls intended for different colors of printing inks, and for different kinds and grades of printing inks may be used and interchanged in the mixing apparatus.

I have exemplified the apparatus as provided with a cabinet 66 in which surplus bowls may be received, the cabinet being provided with hinged doors 67. It may also be provided with rollers 68 so that the apparatus may be moved into close adjacency to the printing press in which the inks are to be used.

The stirrers are further readily removed from the machine so that stirrers for different colors may be employed, in order that the mixing of different colors may take place in quick sequence without the necessity of cleaning stirrers previously used.

The printing press is exemplified at 71, and may be provided with one or more usual ink fountains, exemplified at 72, depending on the number of colors which the press is intended to print, the printing press and fountain or fountains being provided with all usual and ordinary adjustments and devices usual in printing presses, including form rollers.

The proportion of drying or oxidizing agent to the ink depends, as heretofore stated, upon the kind, grade and color of the same, the character of the paper to be printed, and other conditions. I have found, under certain conditions of ink and paper, that an addition to the printing ink, as heretofore manufactured and packed, of five per cent of drying agent, such as a japan drier, which is well-known in the art, or sugar of lead, or other chemical driers, is advisable, although the percentage of drier or oxidizing agent to be added will vary under different conditions of temperature and humidity of air and the other conditions hereinbefore mentioned, and which will be apparent to a person skilled in the art under the teachings herein contained of my improved method.

The stirring of the ink, and of the drying or oxidizing agent when added, may be made at a speed of the stirrer desirably ranging from fifty revolutions per minute

to one hundred and fifty revolutions per minute, more or less, and for a period of five to fifteen minutes, more or less, depending on the consistency of the ink and its ingredients, in order to provide a thorough mixing and aerating of the same.

In my improved method I cause a rearrangement of the ingredients of the ink and a tempering of the ink, and I also introduce air into the ink in order to thoroughly aerate the same, and I thoroughly mix the added drier with the ink, accomplished by thoroughly stirring the same, and render the ink more plastic and more readily flowable. The latter incident may be observed by the fact that the ink will, before treatment by my improved method, be readily supported upon an ink palette knife, whereas, after treatment by my improved method, the ink will readily flow from the ink palette knife.

By my improved method a better distribution of the ink upon the printing surface of the printing types or plates or form, and a more even application of the ink to the printing surface by the inking rollers, are obtained, for applying a film of ink to the printing surface which is more readily transferred to the paper or other material being printed than with ink not treated by my improved method. This further results in economy of ink, as a less quantity of ink is necessary for covering a given printed surface, and more definite and clearer impressions are obtained on the printed surface. The ink treated by my improved method further permits quicker superposing, or so-called "trapping" of colors, as the effect of the addition of the drier or oxidizing agent to the ink and the stirring and aerating of the same immediately before use, is to cause a quicker drying of the ink upon the applied surface, making clearer impressions in color work and other printing possible, and to cause greater affinity between the superposed layers of ink.

My improved method also results in reducing smutting of the printing and of the printed sheets, and off-setting of the printed surface upon the superposed sheets or thicknesses of printed material next to the same, and reduces the likelihood of the printed sheets or thicknesses of printed webs adhering to each other.

My improved method further permits the introduction of such a quantity of drier into the printing ink just before being used, which would be ruinous to stored printing inks, and thereby provides for exceptionally quick drying of the printing ink upon the printed material.

Having thus fully described my invention, what I claim as new, and desire to secure by Letters Patent, is:

1. In the art of printing, the method

which comprises thoroughly stirring previously made ink together with drier added immediately previous to the printing with said ink, and then immediately printing with 5 such ink thus prepared.

2. In the art of printing, the method which comprises stirring, aerating and adding additional drier to a previously made ink immediately before printing with said 10 ink for thus conditioning said ink, and then immediately after such conditioning printing with such conditioned ink.

3. In the art of printing, the method which comprises stirring and aerating a 15 previously made ink in the presence of additional drier added to said ink immediately prior to using said ink in the printing, whereby to increase fluidity of the ink while printing therewith and to increase rapidity 20 of drying of the printed ink, and thereupon

immediately printing with such ink thus treated.

4. In the art of printing, the method which comprises adding a drying and oxidizing agent to a previously made ink and 25 stirring the mixture thereby formed immediately prior to employment of said ink in the printing, whereby to increase the sum of the bulks of said previously made ink and said added drying and oxidizing 30 agent, and thereby aerating the said ink and increasing its fluidity for application to the printing form and increasing the drying and oxidation of the printed ink and reducing off-setting, smutting and sticking of 35 the printed material, and thereupon immediately printing with such ink thus treated.

In testimony whereof, I have hereunto signed my name.

LESLIE W. CLAYBOURN.
